ATTORNEYS

UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

SLUB CATCHER.

Application filed October 28, 1922. Serial No. 597,605.

To all whom it may concern:

Be it known that I, JOHN O. MCKEAN, a citizen of the United States, and resident of Westfield, in the county of Hampden and 5 State of Massachusetts, have invented a new and useful Improvement in Slub Catchers, of which following is a specification.

The object of my invention is to provide a novel form of slub catcher having a yarn clearing hole which will be readily adjustable for yarns of various sizes; through which the yarn may be easily and quickly threaded; and which will not chafe nor scrape the yarn. 15 My invention comprises a slub catcher having two coacting members forming between them a yarn clearing hole, one of the members being movable to change the size of the hole, and also movable to open the hole, means being employed for yieldingly holding the members together.

My invention more particularly comprises a structure in which one of the members has a slot, the walls of which form a portion 25 of the yarn clearing hole and the other member has a rotatively adjustable disc with its peripheral surface disposed lengthwise along said slot to form the remaining portion of the hole, said peripheral surface being graduated circumferentially so that the size of the yarn clearing hole may be readily changed by a rotative adjustment of the disc; means being employed, such for instance as a blade carried by one of the members for deflecting the yarn as it enters the slub catcher, to compel the movement of the said member to open the hole for the proper threading of the yarn.

Practical embodiments of my invention 40 are represented in the accompanying drawings, in which

Fig. 1 represents in top plan a device for guiding, tensioning and clearing yarn, with my invention applied thereto.

Fig. 2 represents a side view of the same.

Fig. 3 represents a front view.

Fig. 4 represents a detail section taken in the plane of the line IV—IV of Fig. 1.

Fig. 5 represents a detail section taken in 50 the plane of the line V—V of Fig. 1.

Fig. 6 represents a detail enlarged section showing the yarn clearing hole adjusted for a yarn of one size, the divergent walls of the slot being shown straight.

Fig. 7 represents a similar view showing 55 the yarn clearing hole adjusted for a yarn of a larger size.

Fig. 8 represents a similar view showing the divergent side walls of the slot as being convex.

Fig. 9 represents a similar view showing the divergent side walls of the slot as being concave.

Fig. 10 represents a similar view showing a graduated peripheral surface of the movable member as comprising a circumferential slot with divergent side walls to form with the slot in the other member a rectangular hole, as distinguished from the triangular holes shown in the other views.

The bracket as herein constructed comprises the longitudinal portion 1 terminating at one end in a turn-back portion 2 and at its other end in uprising ears 3 and 4.

A loop is formed at one side of the portion 1 of the bracket, which loop comprises the lateral branches 5 and 6, connected by the longitudinal branch 7. An arm 8 projects forwardly from the lateral branch 6 to form a suitable yarn support in the ten- 75 sion device.

A pin 9 uprises from the arm 8, upon which pin is loosely mounted the weighted tension disc 10, between which disc and the top surface of the arm 8 the yarn is passed on its way to the slub catcher to be herein-after described. The lug 11 projects laterally from the portion 1 of the bracket in the opposite direction from the branch 6 of the loop, into which lug is screwed the pivot pin 12 on which a vertically yielding lateral swinging guard 13 is pivoted. The vertically yielding movement of this guard is provided for in the present instance by a recess 14, within which there is located a coil spring 15, interposed between the bottom of the recess and the head of the pin 12. The outer end of this washer guard 13 is provided with a portion 16 which projects over the weighted washer 10 and on top of the pin 9 of the tension device when the guard is in its operative position.

Means are provided for yieldingly holding the guard in its operative position, which means is herein shown as a notch and projection connection between the guard and the turned-back portion 2 of the bracket; the notch 17 being formed in the guard and 100 105

the projection 18 being formed on the said turned-back portion.

When the guard is swung back out of its operative position, the weighted washer 10 5 may be readily removed from the pin 9.

The slub catcher for the yarn comprises two coacting members, one having a slot with walls forming a portion of the yarn clearing hole, and the other with a graduated surface forming the remaining portion 10 of the said yarn clearing hole.

In the present instance the fixed member is the branch 5 of the loop hereinbefore described, which branch is shown as provided 15

with a horizontal slot 19 across its upper face, the divergent walls of which slot form two sides of a triangular yarn clearing hole. The other member of the slub catcher is herein shown as comprising a two armed 20 lever pivoted between the lugs 3 and 4 of the bracket on a horizontally arranged pin 21. One arm of this lever may be provided with a handle 22 for manipulating the lever. The other arm of the lever is provided with a 25 rotatively adjustable disc having its circumferentially graduated peripheral surface 24 disposed lengthwise along the horizontal slot 19 of the other member, to form the third side of the triangular yarn clearing hole.

This disc is pivoted to the lever 20 by the screw 25 which passes axially through the disc into the said lever. The disc is provided with a concentric series of holes 26, 30 into one of which holes a pin 27, projecting from the lever 20, projects, for holding the disc in its rotatively adjusted position. This rotative adjustment of the disc is accomplished by loosening the screw 25 sufficiently to permit the lateral movement of the 35 disc, to free it from engagement with the pin 27. The disc is then turned to its proper adjusted position and then moved laterally into engagement with the pin 27, when the screw 25 may be tightened to lock the parts 40 in their adjusted position.

Means are employed for yielding holding the coacting members of the slub catcher together, which means is herein shown as a coil spring 28 extending between the bracket 45 and lever. To open the yarn clearing hole to permit the threading of the yarn, the disc may be lifted out of the slot 19 by depressing the handle 22 of the lever 20 against the tension of the spring 28. It will be 50 understood that the rotative adjustment of the disc will change the size of the yarn clearing hole because of the graduated peripheral surface of the disc, to suit yarns of various sizes; this adjustment of the size of 55 the yarn clearing hole being of a very fine degree so as to ensure the best results in clearing the yarn. It will also be seen that only one yarn clearing hole may be provided, the two coacting members of the slub catcher 60 being capable of adjustment to change the

size of the hole to suit yarns of various sizes and also being capable of movement to open the hole to permit the threading of the yarn.

The reason for the provision of a curved 65 surface on one of the members coacting with the slot in the other member, is to allow the 70 yarn to enter freely into the slub catcher without scraping or chafing the yarn, as would be the case where a square surface is used. When either a thin blade or a square 75 or rectangular block is used, an edge is provided which comes in contact with the yarn on the entering side of the slub catcher. This is avoided in the present invention.

To require the opening of the yarn clearing hole for the proper threading of the 80 yarn through the slub catcher, I provide means for deflecting the yarn as it enters the slub catcher, which means in the present 85 instance I have shown as a blade 29, projecting from the lever 20 of the movable member, the lower edge of which blade is brought into engagement with the yarn, to deflect it when the coacting members are 90 held together. The lifting of the movable member to open the yarn clearing hole will lift the deflecting blade out of engagement with the yarn, thus permitting the ready 95 threading of the yarn through the slot. If the disc of the movable member is not raised to open the slot for threading the 100 yarn, the yarn will be caught or wedged between one side of the disc and one side wall of the slot, thus causing the yarn to break. It is therefore absolutely necessary to open the yarn clearing hole to properly 105 thread the yarn through the slub catcher before the yarn can be wound.

While I have shown the yarn clearing hole 110 in several of the forms as triangular and in another form as rectangular in cross section, it is obvious that the cross section of the hole may be of any desired shape so long as it fills the requirements of the present 115 invention.

It is also evident that various changes 120 may be resorted to in the construction, form and arrangement of the several parts without departing from the spirit and scope of 125 my invention, hence I do not wish to limit myself to the particular embodiments herein shown and described, but

What I claim is:—

1. In a slub catcher, two coacting members, one having a yarn receiving slot and the other having a graduated surface disposed lengthwise along said slot to form a 130 yarn clearing hole, the last named member being movable to bring different portions of said graduated surface within the slot to change the size of the hole, said last named member being also movable bodily to open the hole, and means carried by the movable member for deflecting the yarn before it reaches the hole to require the open-

ing of the hole for the proper threading of the yarn.

2. In a slub catcher, two coacting members, one having a yarn receiving slot and the other having a graduated surface disposed lengthwise along said slot to form a yarn clearing hole, the last named member being movable to bring different portions of said graduated surface within the slot to change the size of the hole, said last named member being also movable bodily to open the hole, means carried by the movable member for deflecting the yarn before it reaches the hole to require the opening of the hole for the proper threading of the yarn, and means for yieldingly holding the members together.

3. In a slub catcher, two coacting members, one having a yarn receiving slot and the other having a curved graduated surface disposed lengthwise along said slot to form a yarn clearing hole, the last named member being rotatively movable to bring different portions of said curved graduated surface within the slot to change the size of the hole, said last named member being also movable bodily to open the hole, and means carried by the movable member for deflecting the yarn before it reaches the hole to require the opening of the hole for the proper threading of the yarn.

4. In a slub catcher, two coacting members, one having a yarn receiving slot and the other having a curved graduated surface disposed lengthwise along said slot to form a yarn clearing hole, the last named member being rotatively movable to bring different portions of said curved graduated surface within the slot to change the size of the hole, said last named member being also movable bodily to open the hole, means carried by the movable member for deflecting the yarn before it reaches the hole to require the opening of the hole for the proper threading of the yarn, and means for yieldingly holding the members together.

5. In a slub catcher, two coacting members, one having a yarn receiving slot and the other provided with a disc having a graduated peripheral surface disposed lengthwise along said slot to form a yarn clearing hole, said disc being rotatively adjustable to bring different portions of said graduated peripheral surface within the slot to change the size of the hole, said disc being also movable bodily to open the hole, and means carried by the movable member

for deflecting the yarn before it reaches the hole to require the opening of the hole for the proper threading of the yarn.

6. In a slub catcher, two coacting members, one having a yarn receiving slot and the other provided with a disc having a graduated peripheral surface disposed lengthwise along said slot to form a yarn clearing hole, said disc being rotatively adjustable to bring different portions of said graduated peripheral surface within the slot to change the size of the hole, said disc being also movable bodily to open the hole, means carried by the movable member for deflecting the yarn before it reaches the hole to require the opening of the hole for the proper threading of the yarn, and means for yieldingly holding the members together.

7. In a slub catcher, two coacting members, one having a yarn receiving slot and the other consisting of a lever pivoted to the first named member and a disc carried by the lever, said disc having a graduated peripheral surface disposed lengthwise along said slot to form a yarn clearing hole, said disc being rotatively adjustable to bring different portions of said graduated peripheral surface within the slot to change the size of the hole, said lever being movable to lift the disc bodily to open the hole, and means carried by the lever for deflecting the yarn before it reaches the hole to require the opening of the hole for the proper threading of the yarn.

8. In a slub catcher, two coacting members, one having a yarn receiving slot and the other consisting of a lever pivoted to the first named member and a disc carried by the lever, said disc having a graduated peripheral surface disposed lengthwise along said slot to form a yarn clearing hole, said disc being rotatively adjustable to bring different portions of said graduated peripheral surface within the slot to change the size of the hole, said lever being movable to lift the disc bodily to open the hole, means carried by the lever for deflecting the yarn before it reaches the hole to require the opening of the hole for the proper threading of the yarn, and means for yieldingly holding the members together.

In testimony that I claim the foregoing as my invention, I have signed my name this 25th day of October, 1922.

JOHN O. McKEAN.
